GAS TORCH

Edwin R. Blahut, Hackensack, N. J., assignor to
 Air Reduction Company, Incorporated, a corporation of New York

Application April 8, 1948, Serial No. 19,664

9 Claims. (Cl. 158—27.4)

1

This invention relates to oxy-fuel gas cutting and scarfing torches.

As is well known to those familiar with the art, a ferrous metal work-piece may be cut or gouged (scarfed) by heating a portion of the work-piece to kindling temperature and then subjecting the heated portion to a high velocity jet of oxygen. All oxy-fuel gas cutting torches are constructed to project a number of preheating flames about the orifice from which the cutting-oxygen issues. The preheating flames are usually fed by a combustible mixture of oxygen and a fuel gas. The most widely used fuel gas for this purpose is acetylene and it will hereinafter be referred to as such, although the term is meant to include any suitable fuel gas. The preheating flames are used for the above-mentioned heating of the metal to kindling temperature, and they are usually left on and projected against the work as the cut progresses because the cut can best be propagated by doing this.

The preheating flames are used alone during the heating of the metal to kindling temperature at the start of the cutting operation and then the cutting-oxygen stream is turned on. The amount of oxygen required by the cutting-oxygen stream is far in excess of that required by the preheating flames. In two-hose torches now in use in which one hose supplies the acetylene and the other hose supplies oxygen for both the cutting stream and the preheating flames, the preheat oxygen is tapped off the cutting-oxygen passage in the torch, and when the cutting-oxygen valve is opened the sudden demand of the cutting jet results in a material decrease in pressure of the oxygen delivered to the preheat mixer and disrupts the balance between the oxygen and acetylene for the preheating flames. Although this is undesirable because it changes the flame characteristics, it has heretofore been tolerated in this type of torch because of the advantages of having only two gas hoses leading to the torch, and to avoid the difficulty it has been necessary to resort to the use of three-hose torches in which one hose supplies the acetylene and the other two hoses separately supply the preheat oxygen and the cutting-oxygen from separate pressure regulators.

The principal object of this invention is to provide a cutting torch which employs only two gas supply hoses and yet maintains substantially constant preheating flames regardless of the rate of oxygen flowing through the cutting orifice.

A cutting torch embodying the invention is

2

illustrated in the accompanying drawings, in which:

Fig. 1 is a side elevation of the torch;

Fig. 2 is a vertical section through the head and tip of the torch shown in Fig. 1, drawn on an enlarged scale;

Fig. 3 is a side elevation of the body portion of the torch shown in Fig. 1, drawn on an enlarged scale, the cutting-oxygen valve associated with the body portion being shown in vertical section;

Fig. 4 is an enlarged rear end view of the torch body;

Fig. 5 is an enlarged longitudinal section of the torch body taken along the line 5—5 of Fig. 4;

Fig. 6 is an enlarged bottom view of the torch body; and

Fig. 7 is an enlarged longitudinal section of the torch body taken along the line 7—7 of Fig. 6.

Referring first to Figs. 1 and 2, the torch comprises generally a body 10, a handle portion 11, a head 12, and a tip 13. Acetylene enters the body 10 through a fitting 14 and oxygen enters it through a fitting 15. The oxygen stream divides in the torch body, as described in detail herein-after, and part of its passes through the cutting-oxygen valve 16 and through tube 17 to the head 12 from which it is delivered to the cutting-oxygen passage 18 in the tip 13. The other part of the oxygen constitutes the preheat oxygen and flows from the body 10 through valve 19 and tube 20 to the head 12 from which it is delivered to the preheat passages 21 in the tip 13. Acetylene entering the body through fitting 14 passes through a tube 22 to the head 12 from which it enters the tip preheat passages 21 and mixes with the preheat oxygen. All parts thus far referred to are conventional with the exception of the torch body 10 which includes novel means for giving the torch its desirable characteristics.

Figs. 3, 4, 5, 6 and 7 are all enlarged views of the torch body. The acetylene passage 23 is drilled straight through the body as is clearly illustrated in Fig. 7. The oxygen enters the body 45 by passage 24. This passage constitutes a portion of the cutting-oxygen passage and is substantially parallel with a preheat oxygen passage 25 (Fig. 5) drilled part way into the torch body from its downstream end. A bore 26 extends 50 transversely into the body portion from one side thereof in such a way as to intersect the preheat passage 25 and to meet the cutting-oxygen passage 24. A tube 27 having a snug fit in the bore 26 is inserted into the bore far enough so that one 55 end will discharge into the preheat passage 25

and its other end will project part way into the cutting-oxygen passage 24. The diameter of the bore 26 and the external diameter of the tube 27 are less than the diameter of the portion 24 of the cutting-oxygen passage. After the tube 27 is positioned, the outer end of the bore 26 is closed by means of a plug or other member 28. The end of the tube 27 which projects into the cutting-oxygen passage has an inlet opening by means of which some of the oxygen in the cutting-oxygen passage enters the tube for delivery to the preheat oxygen passage 25. In the preferred construction, the bore 26 is drilled into the body so that it, and also the tube 27, are inclined in the downstream direction from the cutting-oxygen passage to the preheat oxygen passage, as best shown in Fig. 5, and the inlet end of the tube is bevelled as shown at 29 to form an inlet opening in the cutting-oxygen passage which faces upstream therein. The bevelled inlet end of the tube which projects into the cutting-oxygen passage therefore constitutes a preheat oxygen pick-up which picks up some of the oxygen flowing in the cutting-oxygen passage and directs it into the preheat oxygen passage 25. It might also be said to constitute baffle means for deflecting some of the cutting-oxygen passing through the cutting-oxygen passage into the preheat oxygen passage.

Beyond the preheat oxygen pick-up tube 27, the cutting-oxygen passage leads to the cutting-oxygen valve 16 and then to the cutting-oxygen tube 17.

The cutting-oxygen valve is shown in section in Fig. 3. It comprises a valve seat 30 formed on a portion of the torch body itself. The remainder of the valve assembly is screwed into an internally threaded boss 31 on the torch body. The valve element is shown at 32. The one illustrated is the molded rubber diaphragm type, but any other suitable valve element may be used. Actuation of a lever 33 (see also Fig. 1) in a clockwise direction about a fixed pivot 34 causes withdrawal of a valve stem 35 and the valve element 32 from the valve seat 30 against the action of a coil spring 36. This permits the flow of cutting-oxygen past the valve element. Upon release of lever 33 the coil spring 36 expands and reseats the valve element, thereby stopping the flow of cutting-oxygen. The cutting-oxygen valve has been only briefly described because it does not form a part of the invention.

If the preheats oxygen were delivered from the cutting-oxygen passage to the preheat oxygen passage through an ordinary passage that does not have the tube 27 or its equivalent, there would be a substantial oxygen flow into the preheat oxygen passage 25 when the cutting-oxygen valve 16 was closed and a greatly reduced flow when it was open. This is true because the total head at any point in a fluid stream is equal to the sum of the pressure head and the velocity head. With the cutting-oxygen valve closed the energy of the stream is practically all pressure head, the flow of the preheat oxygen being practically negligible. This relatively large pressure head would provide an adequate supply of preheat oxygen to the preheat oxygen passage from the cutting-oxygen passage. However, when the cutting-oxygen valve is open, the velocity head of the stream increases materially at the expense of the pressure head. This reduction in pressure head would produce a corresponding drop in the amount of preheat oxygen supplied through the ordinary passage leading to the preheat oxygen passage. When a pick-up tube of the kind above described,

or its equivalent, is employed, and the cutting-oxygen valve is closed, approximately the same amount of oxygen will flow through the tube as would flow through the ordinary tubeless passage under the same conditions. However, when the cutting-oxygen valve is open and cutting-oxygen flows, the amount of oxygen flowing through the pick-up tube will not materially decrease because the total head in the pick-up tube is now equal to the sum of the velocity head and the pressure head; or in other words, it is equal to the total head in the cutting-oxygen passage just as it was when the cutting-oxygen valve was closed. This is an application of the familiar Pitot tube principle.

As above stated, the pick-up tube 27 is preferably inclined in the downstream direction from the cutting-oxygen passage to the preheat oxygen passage. This is a convenient construction to manufacture and sufficiently approaches the theoretical Pitot tube construction to give satisfactory results. However, the invention is not limited to a pick-up tube so arranged but includes any kind of a pick-up tube having an inlet opening in the cutting-oxygen passage and facing upstream therein, or similar baffle means, which takes advantage of the velocity head of the oxygen in the cutting-oxygen passage as well as its pressure head to provide a constant supply of preheat oxygen to the preheat oxygen passage regardless of whether the cutting-oxygen valve is open or closed.

I claim:

1. In a gas cutting torch in which a cutting-oxygen passage in the torch controlled by a cutting-oxygen valve and supplied by an oxygen hose delivers cutting-oxygen to the torch tip for discharge thereby, and in which a preheat oxygen passage which taps a quantity of oxygen from the cutting-oxygen passage at the upstream side of the cutting-oxygen valve and a fuel gas passage supplied by a fuel gas hose deliver the tapped preheat oxygen and the fuel gas to a mixing zone where they form a combustible gas mixture which is fed to the preheating flames that are projected from the torch tip, the improvement which comprises baffle means projecting into the cutting-oxygen passage, said baffle means having at least a portion thereof downstream from the upstream side of the entrance to the preheat oxygen passage and arranged to deflect into the preheat oxygen passage an amount of oxygen which remains substantially constant whether the cutting-oxygen valve is open or closed.

2. In a gas cutting torch in which a cutting-oxygen passage in the torch controlled by a cutting-oxygen valve and supplied by an oxygen hose delivers cutting-oxygen to the torch tip for discharge thereby, and in which a preheat oxygen passage which taps a quantity of oxygen from the cutting-oxygen passage at the upstream side of the cutting oxygen valve and a fuel gas passage supplied by a fuel gas hose deliver the tapped preheat oxygen and the fuel gas to a mixing zone where they form a combustible gas mixture which is fed to the preheating flames that are projected from the torch tip, the improvement which comprises a tube which discharges into the preheat oxygen passage and a portion of which projects into the cutting-oxygen passage at the place where the preheat oxygen is tapped from it, the tube being of smaller outside diameter than the diameter of the cutting-oxygen passage and having an inlet opening facing upstream in the cutting-oxygen passage and being constructed and

arranged to deliver to the preheat oxygen passage an amount of oxygen which remains substantially constant whether the cutting-oxygen valve is open or closed.

3. In a gas cutting torch in which a cutting-oxygen passage in the torch controlled by a cutting-oxygen valve and supplied by an oxygen hose delivers cutting-oxygen to the torch tip for discharge thereby, and in which a preheat oxygen passage which taps a quantity of oxygen from the cutting-oxygen passage at the upstream side of the cutting-oxygen valve and a fuel gas passage supplied by a fuel gas hose deliver the tapped preheat oxygen and the fuel gas to a mixing zone where they form a combustible gas mixture which is fed to the preheating flames that are projected from the torch tip, the improvement which comprises a tube which discharges into the preheat oxygen passage and which has a bevelled inner end projecting into the cutting-oxygen passage where the preheat oxygen is tapped from it, said tube being of smaller outside diameter than the diameter of the cutting-oxygen passage, and said bevelled end of the tube providing an inlet opening facing upstream in the cutting-oxygen passage whereby the tube delivers to the preheat oxygen passage an amount of oxygen which remains substantially constant whether the cutting-oxygen valve is open or closed.

4. In a gas cutting torch in which a cutting-oxygen passage in the torch controlled by a cutting-oxygen valve and supplied by an oxygen hose delivers cutting-oxygen to the torch tip for discharge thereby, and in which a preheat oxygen passage which taps a quantity of oxygen from the cutting-oxygen passage at the upstream side of the cutting-oxygen valve and a fuel gas passage supplied by a fuel gas hose deliver the tapped preheat oxygen and the fuel gas to a mixing zone where they form a combustible gas mixture which is fed to the preheating flames that are projected from the torch tip, the improvement which comprises a tube which discharges into the preheat oxygen passage and a portion of which projects into the cutting-oxygen passage where the preheat oxygen is tapped from it, the tube being of smaller outside diameter than the diameter of the cutting-oxygen passage and inclined in the downstream direction from the cutting-oxygen passage to the preheat oxygen passage, said tube having an inlet opening in the cutting-oxygen passage and being constructed and arranged to deliver to the preheat oxygen passage an amount of oxygen which remains substantially constant whether the cutting-oxygen valve is open or closed.

5. A gas torch in accordance with claim 4 in which the inlet end of said tube is bevelled to form an inlet opening lying in a plane substantially at right angles to the axis of the cutting-oxygen passage and which faces upstream in the cutting-oxygen passage.

6. In a gas cutting torch a body portion having a preheat oxygen passage and a cutting-oxygen passage therein, a portion of the cutting-oxygen passage being substantially parallel with a portion of the preheat oxygen passage, a bore extending transversely into the body portion from one side thereof and intersecting said portion of one passage and meeting said portion of the other passage, the bore being of smaller diameter than said portion of the cutting-oxygen passage, a tube inserted into said bore with a snug fit and communicating at one end with said portion of the

preheat oxygen passage, the other end of said tube projecting into the cutting-oxygen passage and having an inlet opening facing upstream therein, and a member closing the outer end of said bore.

7. In a gas cutting torch a body portion having a preheat oxygen passage and a cutting-oxygen passage therein, a portion of the cutting-oxygen passage being substantially parallel with a portion of the preheat oxygen passage, a bore extending transversely into the body portion from one side thereof and intersecting said portion of one passage and meeting said portion of the other passage, the bore being of smaller diameter than said portion of the cutting-oxygen passage, a tube inserted into said bore with a snug fit and communicating at one end with said portion of the preheat oxygen passage, the tube having a bevelled other end projecting into the cutting-oxygen passage and forming an inlet opening facing upstream therein, and a member closing the outer end of said bore.

8. In a gas cutting torch a body portion having a preheat oxygen passage and a cutting-oxygen passage therein, a portion of the cutting-oxygen passage being substantially parallel with a portion of the preheat oxygen passage, an inclined bore extending transversely into the body portion from one side thereof and intersecting said portion of one passage and meeting said portion of the other passage, the inclination of the bore being in the downstream direction of the body portion from the cutting-oxygen passage to the preheat oxygen passage, said bore being of smaller diameter than said portion of the cutting-oxygen passage; an inclined tube inserted into said tube with a snug fit and with one end portion projecting into the cutting-oxygen passage and with its other end communicating with said portion of the preheat oxygen passage, and a member closing the outer end of said bore.

9. In a gas cutting torch a body portion having a preheat oxygen passage and a cutting-oxygen passage therein, a portion of the cutting-oxygen passage being substantially parallel with a portion of the preheat oxygen passage, an inclined bore extending transversely into the body portion from one side thereof and intersecting said portion of one passage and meeting said portion of the other passage, the inclination of the bore being in the downstream direction of the body portion from the cutting oxygen passage to the preheat oxygen passage, said bore being of smaller diameter than said portion of the cutting-oxygen passage, an inclined tube inserted into said tube with a snug fit and communicating at one end with said portion of the preheat oxygen passage, the tube having a bevelled other end projecting into the cutting-oxygen passage and forming an inlet opening facing upstream therein, and a member closing the outer end of said bore.
